SURGICAL CLIP APPLIER

Renzo Guerrini, Florence, Italy

Application April 20, 1935, Serial No. 17,458
In Italy May 3, 1934

10 Claims: (Cl. 1—49.1)

The present invention has for its object an appliance or apparatus for effecting cutaneous sutures by means of gripping members, the said apparatus comprising a magazine containing 5 gripping members and a pincette, or the like, for holding the column of gripping members and which acts under the action of the hand by which it is held, so as to grasp the gripping members, one by one, and to depress, i. e. to flex same, 10 in order to make the points or tips thereof penetrate into the skin, stretch the latter and grip the two flaps or margins to be united.

Essentially, the device is constituted by a rectangular magazine, in the lower portion of which 15 the gripping members are contained, one on top of the other, viz. arranged in a pile (or series), whereas in the upper portion of the magazine there are provided means for pushing the said gripping members constantly downwards, 20 through the interposition of a pressing or sliding block. An opening is provided at the lower end of the magazine and the gripping members are suitably held against passing said opening by the extremities of two resilient limbs constituting the 25 pincette, which serve also the purpose of flexing the gripping members, thereby compelling the same to penetrate into the skin. The two limbs are located at opposite sides of the magazine and provided with means to hold them in 30 contact with the gripping member facing the lower aperture of the magazine.

In one embodiment of the invention—as will be seen hereinafter—suitable means are provided, including, for instance, a rack and a pawl to 35 prevent back feeding of the sliding or pressing block.

The invention will be more precisely understood from the following description, in conjunction with the accompanying drawings which show 40 practical examples of the carrying out of the present invention.

In these drawings

Figs. 1—5 inclusive, show a first example of a pincette according to the present invention, 45 namely,

Fig. 1 shows the complete arrangement in vertical section, with one of the limbs in a divaricating position;

Fig. 2 shows same in an external side view;

Fig. 3 is a horizontal section on line A—B of Fig. 1;

Fig. 4 shows the lower part of the empty magazine in vertical section and

Fig. 5 is a vertical section on line V—V of 55 Fig. 4.

In the figures 6—18, there is shown a further embodiment of the invention, viz.—

Fig. 6 shows the improved pincette in a front view;

Fig. 7 is a side view, partly in section;

Fig. 8 is a rear view;

Fig. 9 is a vertical section of the apparatus;

Fig. 10 is a section on line C—D of Fig. 6;

Fig. 11 is a section on line E—F of Fig. 8;

Fig. 12 shows in a front view the left arm as 10 shown in Fig. 6 of the drawings—for the opening and closing of the limbs;

Fig. 13 is a section on line G—H of Fig. 12;

Fig. 14 is a front view of the right arm as 15 shown in Fig. 6 of the drawings—controlling the limbs;

Fig. 15 is a section on line I—K of Fig. 14;

Fig. 16 shows, apart, in a front view, the sliding or pressing block;

Fig. 17 shows the said sliding block in a plan 20 view;

Fig. 18 is a section on line L—M of Fig. 16.

According to the embodiment illustrated in Figs. 1—5, the invention consists in a rectangular casing 1, forming the body of the instrument, 25 in the interior of which—also rectangular in section—there slides a pressure block 2, guided laterally by two pins 3 moving within two vertical grooves or guideways 4. The pressure block 3 is acted upon by a spiral spring 5, or by any other 30 suitable resilient means. At its upper part, the spring is held by a cover or cap 6. The lower part of the magazine 1 is adapted to accommodate a series of gripping members 7 placed one on top of the other, in a pile. These gripping 35 members may be of the type commonly in use, and also of any other type.

The last gripping member i. e. the one adjacent the lower opening of the magazine 1, is held between two suitably shaped jaws 8 formed 40 at the ends of the flexures 9 of two limbs 10—10, fixed at 11—11 to opposite sides of the magazine, respectively. The said flexures 9 can enter two grooves or guide-ways 12 suitably provided at the bottom of the magazine.

The upper portion 13 of each of the limbs 10 is 45 resilient and tends to divaricate the flexures in order to withdraw the jaws 8 from the lower opening of the magazine 1. Two pawls 14—14 are pivoted at 15 to the magazine, project through openings 16 in the limbs, and emerge from the latter in the shape of knurled knobs, to hold the limbs against the divaricating tendency thereof in a predetermined position, in which the jaws 8 are 50 situated adjacent said opening in the magazine 1. 55

In this position the jaws 8 permit the lowermost clip 7 to enter freely between them under the pressure of the spring 5, whereupon the received clip is prevented from further advancing. 5 When the pawls 14 are pressed upwardly the holding action thereof is interrupted, but this action is restituted when the pawls are depressed again.

The portion of each of the limbs 10 comprised 10 between the knurled knob and the fixed portion 9 is likewise knurled externally, to facilitate the pressing of the limbs toward each other and the deformation of the gripping members.

As shown in Fig. 4, the two longitudinal walls 15 of the magazine 1 are provided at the lower edges thereof with arch-shaped cut outs which allow the skin of being raised on the action of the pincette.

The embodiment of the invention illustrated in 20 Figs. 6-18 comprises likewise a clip magazine for gripping members piled up, one on top of the other. Instead of the pawls 14, 14 there are provided two arms pivoted to the limbs, respectively, to limit the opening of the limbs. The usual rectangular magazine 18 is provided, with two longitudinal grooves 19-20 in opposite walls, respectively, and arch-shaped cut outs 22 at the lower edges of the latter. The groove 19 terminates shortly before the lower end of the magazine 30 whereas the groove 20 opens into the arch-shaped cut out 22 of the corresponding wall. Two limbs or branches are suitably affixed at the upper part of the magazine on opposite sides thereof, by means of screws 25, soldering, etc. The limbs are 35 inwardly flexed at the lower extremities thereof at right angles, and tapered toward the free ends thereof whereby the latter are able to enter grooves 26 provided in the side walls of the magazine 18. The tapered off end of each of the said 40 limbs—viz. the end entering the said grooves—terminates in a small rounded jaw 27 to accommodate, respectively, the two curved extremities of the last gripping member, i. e. of the one ready to be applied. The limbs are of resilient material 45 and have the tendency to divaricate their lower extremities, so as to withdraw the jaws 27 from the opening of the magazine 18.

Two arms, a left arm 28 and a right one 29 are pivoted to the limbs 23, 24, respectively, shortly 50 above the flexures thereof, so as to project inwardly adjacent the wall of the magazine in which the groove 19 is provided. These arms are enlarged at their free ends and provided with Z shaped apertures 30 in the enlarged portions (see 55 Figs. 12 and 14). A screw 32 is secured to the magazine 18 below the terminal point of groove 19 and passes the Z shaped slots 30. A spring 34, wound about a screw 35, is located below the arms 28 and 29 and presses the latter upwardly, whereby 60 the inner end walls of the lower slot portions 31 abut against the screw 32 and hold the arms 28, 29 the limbs 23, 24 and the jaws 27 against the divaricating tendency of the limbs in a predetermined position, in which the lowermost clip can 65 enter between the jaws 27 but cannot pass the same. The cooperation of screw 32 and lower slot portions 31 does not prevent inward movement of the arms 28, 29 when pressure is exerted on the knurled portions 33, 33 of the limbs 23 and 24, in 70 order to deform the lower most clip disposed between the jaws.

The left arm 28 is bent over after the fashion of a roof or ledge 48. When the arms 28, 29 are depressed by finger pressure upon the roof 48, the 75 upper portions 49 of the slots 30 are brought in

alignment with the screw 32 and the arms and limbs can yield further to the divaricating tendency of the latter. Consequently the jaws 27 are automatically withdrawn from the opening of the magazine 18 and the latter is free to receive a new 5 charge of clips.

Within the magazine moves a pressure or sliding organ constituted by a small block 36 provided at its upper part and centrally, throughout the length thereof, with a groove 37 and in said groove with a small vertical slot 38. A horizontal bore 39 accommodates the pin 40 of a pawl 41. The pawl 41 has an elongated shape and tapers at the free end thereof whereby it can project into and slide within the groove 20, with its free end playing freely in said groove for the purpose of engaging and withdrawing a tooth 42 into or from a rack 43, formed on the edge of the groove 20. A small spring 44 inserted into the pin 40 winds about said pin and penetrates with its other end into the opening 38 in the sliding block. This spring, of course, remains housed within the groove 37 of the sliding or pressure block. The block is guided within the magazine by the pawl 41, which moves in the groove 20, and by a screw 40' screwed into the head of the pin 40 moving along the groove 19.

A spiral spring 45 constantly depresses the pressure or sliding block. The teeth of the rack are arranged in such a manner, that they permit downward movement of the block, but prevent the latter from any return movement, viz. from being pushed upwardly from below. In order to enable the said slider to move back freely, the pawl 41 must be so manipulated as to leave the tooth 42 disengaged, whereupon it may be pushed in an 35 upward direction and—when the apparatus is being charged—the pawl 41 may be caused to rest on the portion 46 of the groove 21.

Thus the entire spring 45 is compressed and the lower magazine is free to be charged. 40

At its upper part the magazine carries a small closing plate 47 fitted anyway, dovetailed, for instance, which serves the purpose, on its removal, of enabling the insertion of the spring, and of retaining said spring at the upper portion 45 of the magazine.

In using a pincette according to the present invention the lower mouth of the appliance is placed upon the part to be sutured, while the two limbs of the pincette are pressed together with 50 one hand, whereby both extremities of the limbs of the pincette press upon the gripping member which presents itself, thereby compelling the same to bend; hereupon, the two points or tips of the cup penetrate into the skin and, in 55 bending, raise the skin itself, and bring the two margins into apposition so that the part is raised, entering the arch of the pincette (17 and 22). When the limbs are released again, the applied clip remains in the flesh and the next following 60 gripping member of the pile, being pushed forward by the spring, descends between the jaws, where it is held against further advancing.

Having now particularly described and ascertained the nature of my said invention and in 65 what manner the same is to be performed, I declare that what I claim is:

1. A device for applying agraffes successively to a wound, comprising a substantially straight magazine adapted to accommodate a plurality 70 of agraffes arranged one on top of the other, said magazine having an outlet opening at its end, resilient means within said magazine for urging said pile of agraffes toward said opening, and a pair of opposed pincette limbs articulated to op- 75

- posite sides of the magazine, respectively, the free ends of said limbs being bent at right angles toward each other to form jaws alongside of said outlet opening, said limbs having a resilient tendency to withdraw said jaws from said opening and being adapted to be pressed toward each other to deform an agraffe inserted between said jaws, and releasable stop means holding said limbs and jaws against said withdrawing tendency in a predetermined position.
2. A device for applying agraffes successively to a wound, comprising a substantially straight magazine adapted to accommodate a plurality of agraffes arranged one on top of the other, said magazine having an outlet opening at its end, resilient means within said magazine for urging said pile of agraffes toward said opening, a pair of opposed resilient pincette limbs articulated to opposite sides of the magazine, respectively, the free ends of said limbs being bent at right angles toward each other to form jaws alongside of said outlet opening, said limbs having a resilient tendency to withdraw said jaws from said opening and being adapted to be pressed toward each other to deform an agraffe inserted between said jaws, and releasable stop means holding said limbs and jaws against said withdrawing tendency in a predetermined position, said stop means including aligned slotted arms carried by said limbs, respectively, and a pin carried by the magazine and extending through both slots.
3. A device as set forth in claim 2, in which each of said slots is of zigzag shape, said arms and limbs being normally held in said predetermined position by the lower portions of said slots in cooperation with said pin, but adapted to yield to the divaricating tendency of said limbs, when said arms are depressed to bring the upper portions of said slots in alignment with said pin.
4. A device for applying agraffes successively to a wound, comprising a substantially straight magazine adapted to accommodate a plurality of agraffes arranged one on top of the other, said magazine having an outlet opening at its end, resilient means within said magazine for urging said pile of agraffes toward said opening, two movable jaws at opposite sides of said opening adapted to be pressed toward each other to deform a clip inserted between them, means to hold said jaws normally in a predetermined position, said jaws being formed to permit the lowermost agraffe to enter freely between them and then to prevent the same from further advancing, when they are in said predetermined position, a slideable block interposed between said resilient means and the topmost agraffe of said pile, and releasable means on said block for preventing retractive movement thereof.
5. A device for applying agraffes successively to a wound, comprising a substantially straight magazine adapted to accommodate a plurality of agraffes arranged one on top of the other,
- said magazine having an outlet opening at its end, resilient means within said magazine for urging said pile of agraffes toward said opening, a pair of opposed pincette limbs articulated to opposite sides of the magazine, respectively, said limbs being provided with means alongside of said outlet opening for normally engaging and supporting the lowermost agraffe, a slideable block interposed between said resilient means and the topmost agraffe of said pile, said block having a projecting pin and said magazine having a guide groove for said pin, a rack along said groove, and a tapered pawl carried by said pin and provided with a tooth engageable with said rack.
6. A device as set forth in claim 5, in which the upper end of said groove has a lateral portion into which said pawl may be shifted when it and the block are at their uppermost position.
7. A device as set forth in claim 1, in which said stop means comprises a pair of pawls pivoted to said magazine and releasably engaging said limbs, respectively.
8. A device for applying clips successively to a wound, comprising a magazine adapted to accommodate a plurality of clips, arranged one on top of the other, said magazine having an outlet opening at its end, resilient means for urging said pile of clips toward said opening, two movable jaws at said opening having a tendency to resiliently withdraw from the latter and being adapted to be pressed toward each other to deform a clip inserted between them and releasable stop means holding said jaws against said withdrawing tendency in a predetermined position, said jaws being formed to permit the lowermost clip of freely entering between them and then to prevent the same from further advancing, when they are in said predetermined position.
9. A device, as set forth in claim 2, in which each of said slots is of zig-zag shape, said device comprising further a spring on said magazine pressing said slotted arms upwardly to keep normally the lower portions of said slots in engagement with said pin whereby said arms and limbs are held in said predetermined position, said arms being adapted to yield to the divaricating tendency of said limbs, when said arms are depressed against said spring to bring the upper portions of said slots in alignment with said pin.
10. A device, as set forth in claim 2, in which each of said slots is of zig-zag shape, said arms and limbs being normally held in said predetermined position by the lower portions of said slots in cooperation with said pin and one of said arms having a roof-shaped horizontal projection facilitating depression of said arms in order to bring the upper portions of said slots, in alignment with said pin, whereupon said arms and limbs can yield to the divaricating tendency of the latter.

RENZO GUERRINI.
